UNITED STATES PATENT OFFICE.

W. H. PEASE, OF DAYTON, OHIO.

IMPROVEMENT IN TOBACCO-CUTTERS.

Specification forming part of Letters Patent No. 41,687, dated February 16, 1864.

To all whom it may concern:

Be it known that I, W. H. PEASE, of the town of Dayton and State of Ohio, have invented certain new and useful Improvements in Tobacco-Cutters; and I hereby declare that the following is a true and exact description of the same, reference being had to the accompanying drawings, and to the letters of reference marked thereon.

Figure 1 represents a side elevation of my machine. Fig. 2 represents a plan view. Fig. 3 is a longitudinal vertical section through line $x x$ in Fig. 2. Fig. 4 is a side elevation opposite to the side elevation in Fig. 1. Fig. 5 represents one of the cog-shafts. Fig. 6 represents a section of the endless-chain belt.

The nature of my invention consists in constructing a machine (for the manufacture of "fine-cut tobacco") in such a manner that the tobacco shall be fed by and between a pair of chain-belts so arranged as to form a gradually-contracting throat for feeding and compressing the tobacco, so as to be more readily and finer cut by the cutter operating at the outlet of the throat; also, in the construction of the endless-chain belts; also, in the mode of altering the gearing so as to feed the tobacco with different velocities, according to the required fineness of the cutting; and in the general and particular arrangement of the several devices, all of which is hereinafter fully set forth.

In the drawings, G indicates the rectangular frame-work of cast-iron.

V and W are metallic platforms built within the frame G and reaching nearly across its whole length. These platforms are so arranged as to form between themselves a throat, the widest portion of which is at the end farthest from the cutter; thence they converge to their center; thence they are parallel, thus forming a gradually-contracting throat. (See Fig. 3.) Near the outer ends of these platforms, and a little beyond them, are rollers q and T, and near their inner ends are "cog-shafts" p and p^2 . One of the endless-chain belts, S, passes over the platform V and roller q and cog-shaft P. The other belt, R, in like manner incloses platform W, roller T, and cog-shaft P^2 . When the machine is in operation, the cog-shafts feed the two belts forward in the same direction with equal speed. It will be seen that the belts pass over and hug the faces of the platforms, so

that by this device I have formed a throat, which constantly compresses and swallows that tobacco which is fed into the mouth and discharges it at the outlet as it is shaved off by the revolving cutters.

C is the revolving hub upon the main shaft of the machine. This hub is provided with two wings, C², (which have cutters r r,) extending beyond the hub sufficiently to pass the outlet of the throat, so that when the hub revolves its cutters may strike and graze past the outlet, and thus shear or shave off the tobacco as it is forced out by the chains R and S.

F is the main shaft, having its bearings at t t in the frame G, and extending beyond the frame, so as to receive the hub C. Upon this shaft is the main driving-pulley M and its loose pulley N. Parallel with these pulleys, and quite near them, is a rock-shaft, B², having its bearings in two studs extending out from the frame G. This shaft is provided with a sliding sleeve, D². A screw or stud, 1, passes through this sleeve into a groove (see red lines) in the rock-shaft, so as to allow the sleeve to slide laterally but without turning upon the rock-shaft. The sleeve is provided with a fork, a^2 , for slipping the belt from the fixed to the loose pulley, and vice versa. Upon the end of the shaft B² is a friction-brake, d, which operates upon the rim of the driving-pulley M.

a is a hand-lever affixed to the sleeve D², by which the sleeve is moved laterally, so as to ship or unship the belt, or to press the brake down upon the pulley, so as to speedily stop the motion of the machine.

E² is a cross-shaft, through which motion is conveyed to the belts R and S. This shaft is provided with a large gear-wheel, A², which is driven by one of the worms y or z on shaft F. These worms slide upon their shaft, so that they can be readily put in or out of gear and be held as desired by the screws 2 2. Worm z is constructed with three distinct threads, so that when in gear it will advance wheel A² three cogs at each revolution. Worm y has but one thread, and when it is in gear one of its revolutions advances the wheel A² only one cog.

Upon the opposite extremity of shaft E² (see Figs. 1 and 2) is a gear-wheel, u, secured by a washer and thumb-screw, so that it may be re-

moved and a larger or smaller one be substituted, according to the desired velocity. Wheel u gears into wheel D. Upon the axle I of wheel D is fixed a smaller wheel, L. These wheels D and L move together, and are provided with movable bearings, as will be set forth. Upon one side of the frame are fixed ways or strips f , so as to form a groove or dovetailed slot, k , of a curve described by a radius whose center is at d . e are similar ways nearer the center d , having a similar and concentric slot, e^2 .

g is a piece of metal having three radiating arms, somewhat in shape like a letter Y. It swings on shaft d as a pivot, and is provided with a stud, I, at the junction of the three arms. Its upper extremities are provided with suitable slides and bolts, m and c , working in the slots k and e^2 .

B is a Y-shaped bar, pivoted and partially oscillating upon axle d , and secured at the ends of its forks to the center and one extremity of plate g by means of bolts c and I. It will thus be seen that bar B and plate g together constitute a swinging frame, pivoted at d , so that when it is elevated it will carry with it the wheel D, so as to allow a larger or smaller wheel to be substituted for wheel u . When the substitution has been made, the bolts c and m are tightened and the bearing I becomes sufficiently steady. The small wheel L now takes into the large wheel A, upon whose axle is secured the small wheel b^2 , which gears into the wheel u upon the end of cog-shaft p^2 , and wheel n in turn gears into wheel o upon the end of cog-shaft p .

There is a collar, O^2 , to the gear-wheel A^2 , and it is secured to the shaft E^2 by a set-screw working in a circumferential groove, so as to preclude longitudinal sliding upon the shaft, and to admit of its loosely turning thereon when not held by the clutch. One end of this collar is of the usual form of a "clutch."

Q is a clutch coinciding with the serrated end of collar O^2 and sliding upon shaft E^2 . By means of a screw and slot it is allowed to slide upon, but is prevented from turning around, the shaft.

H is the usual clutch-fork for engaging or disengaging the clutch. The clutch is disengaged to stop the feeding operation.

The endless-chain belts R and S are each composed of several (four or more) chains arranged side by side until a belt of sufficient width is formed. It will be seen that there are cavities (4 4 in Fig. 3) at the articulations between the contiguous links, forming the chains. Now, the several chains composing the belt are arranged side by side in such a manner as to break joints, and thus avoid continuous cavities across the face of the belts. (See Figs. 2 and 6.) Were these cavities or depressions continuous, the tobacco, which is

under great pressure, would lodge in them, and portions of it be arrested in its onward motion to the cutters, and would also seriously tend to clog the action of the machine. The construction of the links is such as to admit of the action of the cog-shafts upon the link-knuckles in the most favorable manner. (See Fig. 3.) These cog-shafts p and p^2 are composed of four cog-wheels upon a shaft, so constructed (see Fig. 5) as to break joints like the belts, in order that the belts may be fed forward without disarrangement.

The belts are tightened as follows: The rollers q and T, over which the belts pass, are provided with sliding journal-boxes f' , which slide in suitable grooves in frame G and fillet U. When I wish to tighten the belts, I have only to drive the wedges s s , which work between the lugs on the inner ends of the sliding bearings and the shoulders s^2 s^2 , and the bearings are forced outward, thus moving the rollers q and T farther from the cog-shafts and distending the belts. Power being applied by belt to pulley M, the cutters are made to revolve with great rapidity, while at the same time, by reason of the descending system of gearing, the feeding and compressing belts are moved forward very slowly. The course of power is as follows: from pulley M on shaft F, through worm y , (or z), to large wheel A^2 on shaft E^2 , thence through small wheel u to large wheel D, thence through small wheel L on shaft of D to large wheel A, thence through small wheel b^2 on shaft of A to small wheel n upon the cog-shaft p^2 , thence to the wheel o of like size upon the other cog-shaft p .

Having thus described my invention, what I claim as new, and desire to secure by Letters Patent, is—

1. The combination of the belts R and S, and platforms V and W, composing a gradually-contracting throat for compressing and feeding the tobacco, constructed and operating substantially as herein described.

2. The belts R and S, when constructed as described, and in combination with a cutting device for cutting tobacco.

3. The swinging frame B g , composed of bar B, and plate g , constructed and operating substantially as described, and for the purposes set forth.

4. The rock-shaft B^2 , in combination with brake d , sleeve D^2 , and lever a , for the purpose specified.

5. The sliding journals f' , wedges s s , and shoulders s^2 s^2 , in combination with rollers q and T, constructed and operating substantially as described.

W. H. PEASE.
